United States Patent Office.

WILLIAM McALLISTER, OF LAWRENCE, MASSACHUSETTS.

Letters Patent No. 78,222, dated May 26, 1868.

IMPROVEMENT IN MACHINERY FOR PRINTING YARN.

The Schedule referred to in these Letters Patent and making part of the same.

Be it known that I, WILLIAM McALLISTER, of Lawrence, in the county of Essex, and State of Massachusetts, have invented a new and improved Device for Holding Yarn while being Printed in the Skein, of which the following is a full, clear, and exact description, reference being had to the accompanying drawings, making a part of this specification, in which—

Figure 1 represents a perspective view of two printing-rolls in a frame, with my improvement applied.

Figure 2 is a plan view of my device for holding the skeins.

The object of my invention is to produce a means for holding the skeins of yarn while passing between the printing-rollers, so that the skeins may be readily handled, and also to insure a more perfect and regular impression upon the yarn during the operation of printing.

And the invention consists in the employment of a piece or sheet of woven wire or wire netting, of a sufficient width to hold the skein, and of any suitable length, upon which any number of skeins may be stretched, so as to be firmly held, and thus passed between the printing-rollers.

In the ordinary method of printing yarn, a great waste is occasioned by the various changes or manipulations required in the operation. The skeins of yarn are taken from the machine or printing-rollers in a wet condition, and transferred to the drying-sticks, by which means they come in contact with each other, and thus become stained. From the drying-sticks they are transferred to the steaming-rods, and then to the washing-tub, where they are washed in single skeins. By my improvement the objections incident to the common process are obviated, inasmuch as the skeins are held and transferred from one operation to another without being removed from the holder.

Referring to the drawings, A A' represent a frame or standards, which support the two printing-rolls, B C, of the ordinary construction. The journals of the upper roll are arranged in elongated bearings, so as to admit of a vertical play of the said roll as the skeins pass between it and the lower roll.

D, fig. 2, represents a piece or sheet of wire netting, of any suitable degree of firmness, and of a width sufficient to stretch the skeins of yarn upon it so as to hold the yarn securely and evenly. The wire netting may be of any convenient length. d d, &c., represent the skeins stretched upon the wire netting, which may contain as many skeins as found desirable. The yielding nature of the wire netting allows the skeins to be readily adjusted upon it. When thus adjusted, the wire netting containing the skeins is passed between the printing-rollers, as shown in fig. 1.

The flexibility of the wire netting admits of its being readily adjusted to the action of the rollers, thus tightening the skeins, and holding them in a position to be favorably impressed by the printing-rolls. The wire netting also allows the coloring-matter to penetrate through the yarn, so as to insure an even impression upon both sides of the fold.

When the wire netting, with the skeins, has passed through the rolls, the whole may be transferred from one operation to another without removing the skeins from the holder.

The device may be used for holding yarns of any description during the process of drying or washing the same.

Instead of the wire netting, a perforated sheet of metal or thin wood may be used, as a holder for the yarn, or such sheet may be solid or without perforations.

What I claim as my invention, and desire to secure by Letters Patent, is—

The holder D, made of wire netting or its equivalent device, for holding skeins of yarn during the process of printing the same, substantially as set forth.

In testimony whereof, I have signed my name to this specification in the presence of two subscribing witnesses

W. McALLISTER.
